UNITED STATES PATENT OFFICE.

JOHN WEHRSCHMIDT, OF CLEVELAND, OHIO.

GAS-ENGINE.

SPECIFICATION forming part of Letters Patent No. 484,168, dated October 11, 1892.

Application filed December 31, 1891. Serial No. 416,668. (No model.)

To all whom it may concern:

Be it known that I, JOHN WEHRSCHMIDT, of Cleveland, in the county of Cuyahoga and State of Ohio, have invented certain new and 5 useful improvements in Gas-Engines, of which the following is a specification.

This invention relates to certain new and useful improvements in gas-engines; and it consists, substantially, in such features of arrangement, construction, and combinations of parts, as will hereinafter be more particularly described and claimed.

The invention has for its object to produce a gas-engine which shall possess the combined 15 characteristics of durability and simplicity, as well, also, as to produce an engine which is not liable to get out of order or be subject to fluctuation during the time it is performing its work.

20 The invention also has for its object to provide an engine of the character referred to which shall be positive in action and one in which each and every part thereof shall always be reliable in operation.

25 The invention has for its still further object to provide a novel arrangement of valves for regulating the number of explosions in the cylinder by the speed of the engine, all as will more fully appear when taken in connection with the accompanying drawings, in which—

Figure 1 represents a side elevation, partly 30 in section, of a gas-engine constructed and arranged in accordance with my invention.

35 Fig. 2 is a vertical sectional view thereof, enlarged, taken through the cylinder and showing the arrangement of valves for regulating the admission of the gas and air as well as the igniting device. Fig. 3 is a similar view

40 showing the valves for effecting the exhaust from the engine and for controlling the admission of the hot gas and compressed air. Fig. 4 is a top plan view of the cylinder and valve-chests. Fig. 5 represents a side elevation, enlarged, the valves and their chests being shown in section. Fig. 6 is a detail view 45 of the spring-actuated sliding bars that are connected with the governor and which serve to control the valves.

50 Before proceeding with a more detailed description it should be stated that the class of engines to which my invention more particu-

larly relates is that in which a mixture of air and gas is exploded within a cylinder at regular intervals to develop the motive power of 55 the engine, the said mixture by its explosive force serving to operate a piston, which in turn communicates its motion to the driveshaft by means of suitable intermediate mechanism. The devices employed are made to 60 operate in such manner as that no loss of motion is incurred, and the engine is maintained at a regular and uniform rate of speed. The gas or vapor after exerting its expansive force is exhausted into a reservoir, from whence it 65 is conveyed back to the cylinder, and, mixing with compressed air, serves to propel the piston forward upon its next stroke. The air is compressed in the lower part of the cylinder by the movement of the piston and is 70 passed through a receiver that is heated by the exhaust from the engine. Thence it passes through a chamber surrounding the upper portion of the cylinder, where its temperature is further raised before entering the cylinder. 75

Reference being had to the several parts of the drawings by the reference-numerals indicated thereon, 1' represents a vertically-arranged cylinder, within which works a reciprocating piston 2, which is connected by a 80 pitman 2' to the engine-shaft 3. This cylinder is made up of two sections (an upper and lower one) bolted or otherwise secured together, and to the upper section are secured two cylindrical valve-chests 4 and 5. The 85 chest 4 is divided into four chambers by means of partitions 6 7 8, which chambers communicate one with the other by means of valve-openings 10, 11, and 12. Connected with the top chamber is a gas-inlet pipe 12', that is provided with a valve 13 for regulating the supply of gas, and with the next adjoining chamber is connected an air-inlet pipe 14. The valve-opening 10 is smaller than the opening 11, in order that the supply of air will exceed 90 that of gas, and said openings are closed by puppet-valves 15 and 16, mounted on a common stem 17 and opening downward. The valve-stem 17 passes through a boss 18 on the top of the valve-chest and is provided at its 100 upper end with a collar 19, between which and the said boss is arranged a coiled spring 20, that normally maintains said valves closed. A cylinder 21 is fitted over the boss tightly,

and thereby prevents the escape of gas. The chamber below the valve-opening 11 communicates with the cylinder 1 by means of a port 21^a, and the valve-opening 12 is closed by a valve 22, mounted on a stem 23, that passes through the lower end of the chest and which is provided near its bottom with a collar 24, between which and the bottom of the chest is arranged a coiled spring 25, which 5 serves to normally keep said valve closed. The chamber below the partition 8 is provided with a port 26, which communicates by means of a passage 27 with a similar port 30 in the chest 5. The chest 5 is provided with four 10 ports 28, 29, 30, and 31, the port 28 being for the admission of compressed air, the port 29 communicating with a reservoir for storing the exploded gas, the port 30 communicating with the port 26 in the chest 4, and the port 20 31 forming an exhaust. The chest 5 is also provided with a port 28^a, which communicates with port 28 and is merely for balancing the valve 37, all as will hereinafter more fully appear.

25 Working within the chest 5 is a cylindrical valve 32, of a sufficient length to cover the ports 28 and 29, and this valve is provided with a series of perforations 33, extending from end to end thereof, for the passage of compressed air, and mounted on the same stem 34, at opposite ends thereof, are integral pistons 35 and 36, which fit and work in the ends of the valve-chest. Loosely fitted upon the valve-stem between the piston 35 and the 30 valve 32 is a cylindrical valve 37, which has a movement upon the stem equal to the width of port 28 and is provided with a metallic packing 38, that so binds the valve within the chest as to prevent it from dropping or low- 35 ering by gravity. Also loosely fitted upon the lower end of the valve-stem above the piston 36 is a cup-shaped valve 39, within which fits the lower portion of the valve 32, the said valve 39 having a movement or play upon the stem equal to the width of the port 30. This 40 valve is also provided with a metallic packing 38^a for the purpose before stated with reference to valve 37. The lower end of the valve- 45 stem 34 passes through the lower end of the valve-chest and is provided near its bottom with a collar 40, between which and the bottom of the valve-chest is arranged a coiled spring 41, the tendency of which is to draw the valve- 50 stem and valves downward.

55 The reference-numeral 42 indicates the reservoir for the hot gas and air which has been exploded in the cylinder, said reservoir being provided with a pipe 43, which communicates with the port 29, the gas after its explosion in 55 the cylinder exhausting from said cylinder through the port 21^a under the valve 22, through the port 26, passage 27, port 30, and by pipe 43 into the reservoir 42. The reservoir 42 is preferably filled or packed 60 with wire-gauze or equivalent material arranged in the form of disks or sheets for the purpose of absorbing heat and maintaining

the heated gases at a high temperature. Said reservoir may, if desired, be connected with one or more reservoirs of similar construction, so as to prevent back-pressure on the piston when the exploded mixture exhausts into said reservoir 42.

The bottom of cylinder 1 is provided with an air-inlet 44 and an outlet 45, within which 75 are seated check-valves 46 and 47, arranged to open and close in opposite directions, and the outlet 45 is connected with a pipe 48, which communicates with an air-receiver 49. The piston 2 in its upward movement within the cylinder will draw in air through the inlet 44 and upon its downward stroke will compress the air and force the same into the receiver, the valves 46 and 47 operating at the same time in an obvious manner. The lower section of cylinder 1 (comprising the air-compressor) has formed within its walls an annular water-space 58, designed to keep said cylinder cool by a supply of cold water.

Within the receiver 49 is arranged a series of vertical tubes 50, similar to the water-tubes of a steam-boiler, which tubes are tapped through heads 51, arranged air-tight within said receiver. The port 31 is connected by means of a pipe 52 with the space in the receiver surrounding the tubes 50, so that the hot exhaust from the engine passes around said tubes and out into the atmosphere through an outlet 53. The compressed air as it passes through said tubes is heated by the hot exhaust, and by means of a pipe 54, which is connected at one end to said receiver and at its other end with an annular chamber 55, formed in the walls of the upper section of the cylinder 1, the compressed air is carried to the said chamber (around the cylinder) and is thereby still further heated. The annular chamber 55 is provided with an outlet-pipe 56, which communicates with the port 28 and is provided with a check-valve 57, which closes said outlet-pipe whenever the pressure in the cylinder exceeds that in the chamber. Such excess of pressure may occur before the valve 37 closes the port 28 on account of the expansion of the hot gases and air in the cylinder 1.

The numerals 59 and 60 indicate push-rods, which slide in bearings 61, secured to the cylinder, and adapted, respectively, to engage the lower ends of the valve-stem 23 and collar 24, as hereinafter described. The push-rod 59 is connected by means of a rod 61^a to a crank-wheel 62, provided upon its periphery with gear-teeth, and this crank-wheel meshes with a gear-wheel 63, mounted on the engine-shaft 3, the gear-wheel 63 being one-half the diameter of the crank-wheel 62, so that the push-rod 59 will only accomplish one full up-and-down stroke during two revolutions of the engine-shaft. The rod 60 is connected by means of a rod 64 to an eccentric 64^a on the engine-shaft, whereby said push-rod will make one complete up-and-down stroke with every revolution of the shaft. At a suitable

point upon the cylinder is secured a horizontal dovetailed bearing-block 65, within which are fitted two bars 66 and 67, that are adapted to slide back and forth in said block. Said bars at their adjacent ends are provided with upturned perforated ears 68 and 69. In the ear 68 is rigidly secured a rod 70, which passes loosely through the perforated ear 69 and at its free end is provided with two jam-nuts 71. Arranged upon the rod 70, between the ears 68 and 69, is a coiled spring 72, and a similar spring 73 is disposed between the ear 69 and nuts 71, whereby the said bars may have a limited movement independent of each other. At suitable points on said bars 66 and 67 are secured vertically-disposed lugs 74 and 75, the tops of which are beveled, as shown, to form knife-edges 76 and 77 at the upper and inner edges of said lugs. The lower and outer edges of the collars 24 and 40 are recessed at 78 and 78^a, said recesses being adapted to be engaged by said lugs and raise the valve-stems 25 and 34 up out of engagement with the push-rods 59 and 60 in the manner hereinafter explained. Pivotaly connected to the outer end of bar 66 is a link 80, which in turn is pivoted to one arm of a pivoted bell-crank lever 81, the other end of said lever being engaged by the sliding collar 82 of a centrifugal governor 83, and as the speed of the engine increases and the collar 82 is raised the bell-crank lever and pivoted link draw the bar 66 to the right and operate the valves that control the engine, as will hereinafter appear.

The ignitor for exploding the mixture of gas and air within the cylinder is constructed as follows: The top of the cylinder is provided with a valve-opening 84, in which are arranged oppositely-disposed puppet-valves 85 and 86, carried by a valve-stem 87. The distance between the valves is such that one valve will be open when the other is closed, and vice versa. Over the valve-opening the cylinder is provided with a hollow boss 88, perforated at its top, and within said perforation is tapped a hollow screw-threaded nut 89, through which passes the upper end of the valve-stem 87. A coiled spring 90 is arranged on said valve-stem between the nut 89 and valve 85 and exerts its force to close said valve, the tension of this spring being adjusted by means of the nut 89. The hollow boss 88 is provided with a lateral opening 91, which communicates with a tube 92, in which is arranged a gas-burner 93, connected with a suitable gas-supply pipe 94. In operation the valve 85 is normally kept closed by the spring 90; but when the piston is on its downward stroke it draws into the cylinder a mixture of air and gas and on its upward stroke will force a portion of the mixture into the space between the valves 86 and 85, and when in its upstroke the piston compresses the gas and air within the cylinder the valve 86 will close and open the valve 85 and the gas in the space between the valves 85 and 86 will become ignited from the flame of the burner 93, and as the piston starts on the return stroke the valve 85 closes, the valve 86 opens, and the burning air and gas in the space between 70 said valves will ignite the compressed gas and air in the cylinder and explode the same above the piston.

The operation is as follows: As before described, the push-rods 59 and 60 are so geared with the engine-shaft that the rod 59 is moved up and down only once in two revolutions of said shaft, while the rod 60 makes one full up-and-down stroke at every revolution of the shaft. Now when the engine is at rest the 80 governor will draw the bars 66 and 67 toward the left and the valve-stem 23 will be forced down into position to be engaged by the push-rod 59 and the valve 22 closed, while the valve-stem 34 will be held up (the collar 40 resting 85 on the lug 75) and the valve 32 in raised position. To start the engine, power is applied to the shaft by hand in order to move the piston. The piston on its downstroke creates a partial vacuum above it and opens the valves 90 15 and 16 and admits a quantity of gas and air to the cylinder through the port 21^a. Upon the upstroke of the piston the valves 15 and 16 are closed and the gas and air compressed, and upon the return stroke the mixture is 95 ignited and exploded, as before stated, the piston being propelled downward. Upon the return upward stroke the push-rod 59 will lift the valve 22, and the exploded mixture will be forced by the piston through the port 100 26 and passage 27 and thence through the port 30 and pipe 43 into the reservoir 42. In the movement of the piston up and down within the cylinder it has been compressing and forcing air, as before described, into the 105 receiver 49 and up into the chamber 55 in the upper wall of the cylinder, the air being first heated in the receiver and further heated in said chamber. This operation is repeated continuously, and when the speed 110 of the engine becomes too great the governor acts to force the bars 66 and 67 toward the right, and as soon as the push-rod 59 has raised the valve-stem 23 the lug 74 passes under the recessed collar 24 and holds 115 the valve 22 open. As the bar 66 is forced toward the right the spring 72 is compressed between the ears 68 and 69, and when the push-rod 60 engages the valve-stem 34 and slightly raises the collar 40 from engagement with the lug 75 the bar 67 is forced by 120 said spring to the right and the spring 41 forces the stem 34 downward and starts the valves in casing 5 into motion. At this moment the valve 22 is open and the ports 125 between said valves and the receiver are also open and the piston upon the first part of its downward stroke. The gas from the receiver 42 passes back into the cylinder, and when the piston has performed about one-third of 130 its downstroke the valve 32 in moving down closes the port 29 and simultaneously opens port 28. This cuts off the supply of gas from the receiver and permits the entrance of the

heated compressed air through the port 28, through the valve 32, and into the cylinder through the same ports by which the gas from the receiver passed. As the compressed air mingles with the hot gas its volume and temperature are increased, and, expanding, drives the piston upon its downstroke. When the piston has completed about one-half of its downstroke, the valve 37 closes the port 28, shutting off the entrance of compressed air, and as the piston arrives near the end of the stroke the valve 32 forces down the valve 39 and opens port 31, and at the upward or return stroke of said piston the contents of the cylinder are discharged through the ports 21, 26, 27, 30, and 31, through the pipe 52, and thence through the compressed-air receiver 49 to the atmosphere. When the piston is making its return upstroke, the valve 39 is raised by the piston 36 and closes the exhaust-port 31, and at the same time the valve 32 has commenced to open the port 29 again to admit gas to the cylinder, and upon the return stroke of the piston the before-described operation of the valves is repeated. As the speed of the engine decreases the governor will act to draw the bars 66 and 67 toward the left, and when the collar 24 is slightly raised by the push-rod 59 it will disengage the lug 74 from the collar and the bar 66 will be drawn to the left and the stem 23 forced down by the spring 25, thereby closing the valve 22 and allowing the stem 23 to be operated by the push-rod 59. When the bar 66 is drawn to the left by the governor, the spring 73 is compressed between the nuts 71 and the lug 69 of the bar 67. As the valve-stem 34 is raised by the push-rod 60 the collar 40 releases the lug 75 and the spring 73 forces the bar 67 to the left, and as the push-rod 60 goes down said collar rests on the lug 75 and holds the valves or the stem 34 up and in a position to permit passage of the heated gas from the receiver to the cylinder. At the beginning of the downstroke of the piston the valve 22 closes and the valves 15 and 16 open, admitting air and gas, and when the piston returns upon its upstroke the air and gas are compressed and ignited, as before described. As further explanatory of the operation it may be stated that when the valve 32 starts to move upward it pushes the valve 37 with it and prevents the compressed air from entering the cylinder again. From the foregoing it will be understood that a great economy in the amount of gas consumed is effected, for by exhausting and storing up the gas after it has been exploded in the cylinder and combining it with compressed air heated by the exhaust from the engine, power is developed to propel the piston that would otherwise be wasted, compelling repeated and uninterrupted explosions of gas to keep the engine running. Further, a great saving is also effected by automatically regulating the number of ex-

plosions in the cylinder by the speed of the engine.

Having thus described my invention, what I claim as new, and desire to secure by Letters Patent, is—

1. In a gas-engine of the character described, the combination, with the cylinder, the piston, and an igniting device, of gas and air supply inlets, a discharge-passage communicating with a reservoir, a valve controlling the discharge-passage, valves controlling the gas and air inlets, a compressed-air receiver communicating with the said discharge-passage, and valves arranged between the cylinder and the reservoir and air-receiver, and mechanism connected with the engine for operating the said valves, whereby gas and air are first supplied to the cylinder and exploded to propel the piston, the exploded gases discharged into the reservoir and subsequently passed back into the cylinder, and a supply of compressed air admitted to the cylinder to combine with the gas from the reservoir, as set forth. 90

2. In a gas-engine of the character described, the combination, with the cylinder, piston, and igniting device, of a valve-chest communicating with the cylinder and provided with valved gas and air inlet ports and a discharge-port, a valve controlling said discharge-port, a valve-chest provided with a port communicating with said discharge-port and also provided with ports communicating, respectively, with a compressed-air receiver, a reservoir, and an exhaust, valves controlling said ports, and mechanism for actuating said valves to automatically admit gas and air to the cylinder to be exploded and propel the piston, besides discharging the exploded gas into the reservoir and conveying it back into the cylinder and finally exhausting the exploded gas and compressed air, substantially as set forth. 105

3. In a gas-engine of the character described, the combination of the cylinder, one end whereof is an air-compressor, and the piston, a chamber communicating with the cylinder and provided with valved gas and air supply ports and with a discharge-port, a valve controlling said discharge-port, a chamber provided with a port communicating with said discharge-port and provided with a compressed-air-supply port, a gas-port, and an exhaust-port, valves controlling these ports, a reservoir communicating with said gas-port, an air-receiver communicating with the air-compressor, a pipe connecting said receiver with a chamber surrounding the cylinder, a passage connecting said chamber with said compressed-air-supply port, and a pipe connecting the exhaust-port with the air-receiver. 125

4. In a gas-engine of the character referred to, the combination, with the cylinder, piston, and igniting device, of gas and air supply inlets, valves normally closing said inlets, a discharge-port, a valve controlling said port, said

gas and air valves opening on the downstroke of the piston when the discharge-port is closed, a compressed-air receiver, and a gas-reservoir, an exhaust-port, valves controlling said ports, mechanism connected with the engine for actuating the valves, and a governor driven by the engine and alternately throwing said valves in and out of operation, whereby the engine is alternately operated by exploding gas and air and by the mingled exploded gas and compressed air, substantially as set forth.

5. In a gas-engine of the character described, the combination, with the cylinder, piston, and igniting device, of gas and air inlet valves, a discharge-valve, a gas-reservoir, a compressed-air receiver, valves controlling communication between said reservoir and receiver and the discharge-valve, mechanism driven by the engine for actuating the valves, and mechanism actuated by the engine-governor for alternately throwing said valves in and out of operation, whereby gas and air are exploded within the cylinder 25 to propel the piston and the exploded gas utilized by discharging the same back into the cylinder and combining compressed air therewith to propel the piston by expansion, as set forth.

30 6. In a gas-engine of the character described, the combination, with the cylinder, piston, and igniting device, of an exploded-gas reservoir, a compressed-air receiver, passages connecting the cylinder and the said reservoir and receiver, an exhaust, valves controlling said passages and exhaust, mechanism driven by the engine for engaging the stems of said valves and actuating the same, collars fixed on the valve-stems, sliding bars 40 provided with lugs adapted to engage said collars, and a governor driven by the engine and operating said sliding bars to alternately cause said lugs to engage said collars and hold said valves out of engagement with the actuating mechanism, substantially as described.

7. In a gas-engine of the character described, the combination, with the cylinder, piston, and igniting device, of valved gas and air inlets, the gas-reservoir and compressed-air receiver, the connecting passages and valves and the exhaust-port, collars carried by the valve-stems, mechanism driven by the engine for engaging the valve-stems and actuating the valves, and sliding bars provided with lugs and actuated by a governor driven by the engine to cause the lugs to alternately engage said collars and hold the valves out of engagement with the valve-actuating mechanism, as set forth.

8. The combination, with the cylinder, piston, and ignitor, of the valved gas and air inlets, the exploded-gas reservoir, and compressed-air receiver, the connecting passages 65 and valves, and the exhaust-port, collars carried by the valve-stems and having angularly-recessed bottoms, mechanism driven by the

engine for engaging the valve-stems and actuating the valves, and sliding bars provided with beveled lugs and actuated by a governor 70 driven by the engine to cause the lugs to alternately engage said collars and hold the valves out of engagement with the valve-actuating mechanism, substantially as shown and set forth.

9. The combination, with the cylinder, the exploded-gas reservoir, the compressed-air receiver, and the connecting passages and valves, of the valve-stems provided with collars 24 and 41 for depressing the valve-stems, push-rods 80 59 and 60, driven by the engine, for elevating the valve-stems, sliding bars 66 and 67, loosely connected and carrying the beveled lugs, a spring for forcing said bars apart, a spring for forcing them together when released, and a 85 governor driven by the engine, connected to one of said sliding bars, and operating to cause said lugs to alternately engage said collars and hold the valve-stems out of engagement with the push-rods, as set forth. 90

10. The combination, with the cylinder, the exploded-gas reservoir, the compressed-air receiver, and the connecting passages and valves, of the valve-stems provided with collars 24 and 40, having angularly-recessed bottoms, 95 springs 25 and 41 for depressing the valve-stems, push-rods 59 and 60, adapted to engage and elevate said stems, mechanism for actuating said push-rods, the said push-rod 60 being actuated twice while the rod 59 is 100 actuated once, sliding bars 66 and 67, carrying beveled lugs and loosely connected together, a spring for forcing said bars apart, a spring for again forcing them together, and a governor driven by the engine, connected to 105 one of said sliding bars and operating to cause said lugs to alternately engage said collars and hold the valve-stems out of engagement with the push-rods, as set forth.

11. In a gas-engine of the character described, the combination, with the cylinder, piston, and ignitor, of the valve-chest 4, communicating with the cylinder and provided with valved gas and air inlets and a discharge-port 26, a valve 22, actuated by the 110 engine for closing said port, the valve-chest 5, provided with ports 28, 29, 30, and 31, the port 28 communicating with a compressed-air supply, the port 29 with a reservoir for storing exploded gas, the said port 30 communicating with the said port 26, and the port 31 with an exhaust, the valve-stem 34, carrying the fixed perforated valve 32 and the pistons 35 and 36, and the sliding valves 37 and 39, carried by the stem and having 125 lost motion thereon, mechanism driven by the engine for actuating said valves, and a governor also driven by the engine for automatically throwing said valves in and out of operation as the speed of the engine increases 130 and diminishes, as set forth.

12. The combination, with the cylinder, the exploded-gas reservoir, and compressed-air receiver, of the valve-chest 4, communicating

with the cylinder and provided with valved gas and air ports and a valved discharge-port, the valve-chest 5, communicating with said discharge-port and provided with ports communicating with the reservoir and air-receiver and with an exhaust, the valve-stem 34, carrying a perforated valve adapted to alternately open communication between the discharge-port and the reservoir and air-receiver, the valves 37 and 39, loosely mounted on said stem and having lost motion thereon, the said valve 37 controlling the admission of compressed air and the valve 39 controlling the exhaust, pistons 35 and 36, respectively mounted above and below said valves 37 and 39, and mechanism for operating these valves, as set forth.

13. In combination with the cylinder, exploded-gas reservoir, and compressed-air receiver, the valve-chest 4 and its inlet and outlet ports and valves, the valve-chest 5, communicating with the chest 4 and provided with ports leading to the reservoir and air-receiver, a check-valve located between said receiver and air-port, the valves 32, 37, and 39, controlling said ports, and a balance-port communicating with the compressed-air port and adapted to admit air above the valve 37 to balance said valve, as set forth.

14. In a gas-engine, the combination, with a cylinder and piston and gas and air inlets, 30 of an igniting device consisting of the double puppet-valves 85 and 86, seating in an opening in the end of the cylinder, said opening communicating with a hollow chamber provided with an orifice arranged opposite to a 35 gas-burner, and a spring for normally holding the valve 85 closed and valve 86 open, but yielding to permit the reversal of said valves when the gas and air in the cylinder is compressed by the piston, as set forth. 40

15. In an igniting device for explosive-gas engines, the combination, with the cylinder and piston, of the hollow boss 88, communicating by an opening with said cylinder, double puppet-valves 85 and 86, seated in said 45 opening, a hollow nut 89, tapped in said boss and guiding the valve-stem, a spring arranged between said valves and nut, and an orifice in said boss located opposite a gas-burner, as set forth. 50

In testimony whereof I affix my signature in presence of two witnesses.

JOHN WEHRSCHMIDT.
